JOHN MARTIN, OF COLTON, CALIFORNIA, ASSIGNOR OF ONE-HALF TO JAMES HEATLY,
OF COLTON, CALIFORNIA.

AUTOMATIC RAILROAD-SWITCH.

1,259,259.

Specification of Letters Patent. Patented Mar. 12, 1918.

Application filed August 30, 1916. Serial No. 117,725.

To all whom it may concern:

Be it known that I, JOHN MARTIN, a citizen of the United States, residing at Colton, in the county of San Bernardino and State 5 of California, have invented new and useful Improvements in Automatic Railroad-Switches, of which the following is a specification.

This invention relates to a railway switch 10 and particularly pertains to an automatically operated switch for use with either steam or electric cars.

It is an object of this invention to provide a railway switch which may be electrically operated by a moving train and which will automatically open a switch and thereafter close it, said operation being controlled from the cab of the engine.

Another object of this invention is to provide 20 simple and positively operating means for closing the electric switch operating circuits and insuring that they cannot be closed or opened except when a train is passing over the track adjacent the switch.

Another object is to provide a switch operating mechanism which is adapted to be moved to actuate the switch manually when so desired and which may be locked in an inoperative position so as to permit the electrically operated mechanism to open and close the switch without difficulty.

Another object is to provide means whereby a semaphore may be actuated simultaneously with the switch movement and will indicate visually the open or closed position of the switch. It is a further object to provide a mechanism of the above class which may be easily applied for use upon railroad right-of-ways without great expense and which may be maintained without an elaborate equipment or an extraordinary amount of care.

Other objects will appear hereinafter.

The invention is illustrated, by way of 45 example, in the accompanying drawings in which:

Figure 1 is a view in diagram illustrating a section of railway track and a switch connected therewith, as seen in plan, and further illustrating in a diagrammatical manner the arrangement of the various electric circuits and their relation to the switch and its actuating mechanism.

Fig. 2 is a view in plan illustrating a main line track upon which a locomotive

is shown as traveling, and further illustrating the control arm fixed to the cab, and the trip mechanism actuated thereby.

Fig. 3 is a view in side elevation showing the switch actuating trip mechanism in section and further illustrating in dotted lines the relation of the engaging arm, mounted upon a locomotive, to said trip mechanism.

Fig. 4 is a view in vertical transverse section as seen through the switch actuating mechanism and the rails and switch effected thereby.

Fig. 5 is a view in plan and illustrates the disposition of the switch mechanism in relation to the track.

Fig. 6 is a view in section and elevation taken along the side of the primary actuating mechanism.

Referring to the drawings more particularly, 10 and 11 indicate parallel rails of a main line railway track and 12 and 13 indicate the parallel rails of a side track which connect with the main track. The movement of a car from the main track to the side track is controlled by a customary switch which is composed of a straight rail member 14 adapted to form a continuation of the rail 10 between the side track rails 12 and 13 and a curved rail 15 which is suitably secured in a pivoted manner with the rail 14 to a frog 16.

The rails 14 and 15 are adapted to be horizontally moved by means of a switch arm 17 which is pivotally mounted upon a substructure 18 and is formed with gear teeth 19 around its pivotal center. These teeth are disposed to engage the teeth of a horizontally sliding gear rack 20 which rests upon the structure 18 and is formed with an extension 21 which extends beneath the rails 10 and 11 and upon which the switch rails 14 and 15 are mounted and adapted to be actuated to open and close the passage of a car to the side track.

The switch arm 17 allows the switch to be manually operated when desired. It is, however, the principal object of this invention to provide mechanical means for actuating the rack and its extension 21. This is accomplished by a lever arm 22 which is pivotally mounted upon the substructure 18 and is actuated by a switch shifting electromagnet 23. The magnet is electrically connected, by means of a conductor 24, to a contact point 25 of a switch

provided with a contact blade 26. The blade 26 is electrically connected, through conductors 27 and 28, to a source of electrical energy 29, the opposite pole of which is 5 grounded by a conductor 30 and permits a flow of current to pass to the electromagnet 23 through a ground wire 31 and when the switch blade 26 is in contact with the contact point 25 the magnet 23 will be energized to draw the arm 22 in the direction of the arrow —a— against the opposition of a recoil spring 32 which normally holds the straight rail section 14 in alinement with the rail 10 and the curved rail section 15 10 out of contact with the rail 11.

The switch blade 26 is adapted to be housed within a vertical housing 33 which is rigidly secured at the side of the main track rail 10. This housing is provided with 20 vertically disposed bearings 34 and 35 through which plunger rods 36 and 37 are fitted, respectively. The plunger rod 36 is in connection with the contact blade 26 and is held in its uppermost position by a spring 25 38 which bears between the bearing 34 and a collar 39. The plunger 37 is mounted within the bearing 35 in superimposed relation to the plunger 36 and is adapted to be brought into engagement with the end of 30 plunger 36 by means of a crank arm 40 which is pivoted for vertical movement and which, when moved, will cause downward movement of plungers 37 and 36 to produce electrical contacts between contact members 35 25 and 26. The arm 40 is formed with a horizontally extending shaft 41 which extends outwardly through the housing toward the track and is fitted with a tripping arm 42 which is adapted to be engaged 40 by an actuating lever 43. The lever 43 is pivoted to swing horizontally from a suitable point upon the locomotive 44 and its movement is controlled by the engineer. The trip lever 42 is formed with a lever arm 45 which a counterweight 46 is secured upon. The counterweight is provided to maintain the lever 42 in a normal position, as indicated in Fig. 3 of the drawings, and is adapted to rest upon a lug 47 formed on the 50 side of the housing 33.

In order to insure that the switch may be locked during the passage of the train along the track, an auxiliary electric circuit is provided which is operated by the weight of a 55 car passing along the rail, and will, when operated, release a locking device which acts to temporarily lock the switch rail members in a closed position. This mechanism is composed of a vertically movable rail section 48 which is supported upon cross-ties 49 and 50. This section is a portion of the main-line rail 10 and due to the distance between the cross-ties 49 and 50 will be deflected in a downwardly direction as indicated by the arrow —b— in Fig. 6. The

downward movement of this portion of the rail causes the upper contact member 51 to be depressed and to form a contact with a lower contact member 52. The member 51 is electrically connected by a conductor 53 70 to the source of electrical energy 29, the contact 52 being connected by a conductor 54 to one pole of an electromagnet 55, the other pole of which is grounded. When a flow of current is established through the electromagnet 55, a lever arm 56 will be drawn against the magnet and will swing a locking arm 57 in an upwardly direction. The locking arm 57 is formed with a notch 58 along its upper edge and this is adapted to be engaged by a locking pin 59 which is suitably secured to a semaphore standard 60 adapted to be rotated by a link 61 secured to the rack-bar 20. The locking arm 57 is provided with a counterweight 62 which will 80 hold the notch 58 in engagement with the pin 59 when the switch is closed. The counter-weight is mounted upon an upwardly extending portion of the locking arm 57, it being so disposed in relation to the 85 arm and the magnets 55 and 68 as to swing each way over the pivotal center of the arm and hold the arm in its uppermost and lowermost positions. This insures that when the arm is momentarily actuated by either 90 of the magnets, it will remain in its actuated position until effected by the opposite magnet. 95

After the train has passed on to the side-track, a rail portion 63 will be depressed 100 and this will move a contact 64 into engagement with a contact 65, thus completing a circuit through a conductor 66 leading to the source of electrical supply 29, and a conductor 67 leading to one pole of a magnet 105 68. The opposite pole of the magnet and the source of electrical supply are grounded to complete the circuit. The magnet 68 is in an opposed position to the magnet 55 and, when given a magnetic impulse, will act 110 upon the lever arm 56 to draw the locking arm 57 downwardly and prevent the engagement of the slot 58 with the pin 59. The counterweight arm 62 will retain the arm 57 in its lowermost position after the circuit 115 has been broken. The movement of the locking arm 57 to disengage the pin 59 permits the recoil spring 32 to draw the switch members in a position indicated by the arrow —c— and automatically restores the switch 120 rail 14 to form a continuous main-line right-of-way.

The manner in which the switch is automatically opened and closed by a passing train is as follows:

The engineer, when desiring to enter the switch, swings the actuating lever 43 outwardly from the cab of the engine, as indicated in Fig. 2 of the drawings. As the train approaches the switch, it will pass over 125 130

the rail section 48 and complete an electric circuit through the contacts 51 and 52, the conductors 53 and 54, the electromagnet 55, and the battery 29. This, as has been described, will cause the locking lever 57 to be swung upwardly ready to lock the switch when it is moved to a closed position. The lever will be held in this position by a counter-weight which has been swung rearwardly 10 and centered and will yieldably support the lever so that the lock pin may swing into the notch thereupon, thus locking the switch against rotation until the lever and its weight are again swung by the magnet 68 15 and then released. As the engine approaches the switch, it will pass the trip-lever 42 and the actuating lever 43 will strike it and force it downwardly in the direction of arrow —d— in Fig. 3 of the drawings. As 20 the lever 42 swings downwardly, it will cause a downward vertical movement of plunger rods 36 and 37 and these in turn will bring contact 26 into engagement with contact 25 to complete an electrical circuit 25 through conductors 27 and 28 to the battery 29 and through the conductor 24 to one side of the electromagnet 23, the opposite poles of the magnet and battery being grounded to complete the circuit. The electromagnet 23 now being energized, will 30 draw the switch arm 22 and this will act to draw the rack-bar 20 and the switch rails 14 and 15, which are mounted upon the extension 21 of said bar. This movement will 35 cause the curved rail 15 to form a continuous rail from the main-line rail 11 and will draw the rail 14 away from the main-line rail 10 to open the switch. After the train has passed through the switch and has 40 drawn near the other end of the siding, the rail section 63 will be encountered and will be depressed to complete the circuit through the electromagnet 68. This circuit will energize the magnet and thereby lower the 45 locking lever 57 to permit the recoil spring 32 to re-draw the switch rails to close the side-track and restore the main-line right-of-way.

It will thus be seen that the switch here 50 provided will act automatically, upon the approach of a train, to open a side-track, and will positively insure that the switch is restored to its closed position after the movement of the train therethrough.

55 I claim:

1. In an automatic railway switch, the combination with a main line track, a side track, and switch members adapted to be moved to establish and discontinue communication between the main line track and the side track, of switch operating mechanism comprising an electrically controlled and actuated switch moving mechanism, means controlled from a moving train whereby 60 said switch moving mechanism is actuated,

means automatically and indirectly operated by the weight of the train whereby said switch moving mechanism will be locked as a train moves along the switch members, and other means indirectly operated by the 70 weight of the train whereby the moving mechanism will be released to allow the return of the switch to its normal position.

2. In an automatic railway switch, the combination with a main line track, a side 75 track, and switch members adapted to be moved to establish and discontinue communication between the main line track and the side track, of switch operating mechanism comprising an electrically actuated switch control, optionally actuated means positioned upon a moving train whereby said switch control may be actuated, means indirectly operated by the weight of an approaching train whereby the switch control will be rendered inoperative during the passage of a train along the switch members, positively operated means for controlling said switch control, and means operated by the weight of the train after it has passed the switch to release the locking mechanism and permit the switch to return to its normal position.

3. A switch operating mechanism, comprising an electrically controlled and actuated switch moving mechanism, means controlled from a moving train whereby said switch moving mechanism is actuated, means automatically and indirectly operated by the weight of the train whereby said switch moving mechanism will be locked as a train moves along the switch members, and other means indirectly operated by the weight of the train whereby the moving mechanism will be released to allow the return of the switch to its normal position.

4. A switch operating mechanism, comprising an electrically actuated switch control, optionally actuated means positioned upon a moving train whereby said switch control may be actuated, means indirectly operated by the weight of an approaching train whereby the switch control will be rendered inoperative during the passage of a train along the switch members, positively operated means for controlling said switch control, and means operated by the weight of the train after it has passed the switch to release said switch control mechanism and permit the switch to return to its normal 1 position.

5. In an automatic railway switch, the combination with a main-line track and a side-track, of switch members adapted to be moved to establish and discontinue communication between the main-line and the side-track, manually and automatically controlled switch moving means, an optionally controlled trip member positioned upon the side of a car passing along the track, trip means

engageable by said member whereb, the switch will be automatically closed, an electrically operated switch lock for temporarily holding the switch in its closed position, 5 electric contact means actuated by the weight of the train passing along the track whereby said switch lock mechanism will be caused to operate, electrically operated means for

releasing the switch lock, other electric contact means for actuating said releasing means, and a spring by which the switch will be restored to its normal open position after the locking means has been released.

In testimony whereof I have signed my name to this specification.

JOHN MARTIN.
